Inventor

UNITED STATES PATENT OFFICE.

JOHN STULL, OF PHILADELPHIA, PENNSYLVANIA.

STEREOSCOPE-CASE.

Specification of Letters Patent No. 12,451, dated February 27, 1855.

To all whom it may concern.:

Be it known that I, JOHN STULL, of the city of Philadelphia and State of Pennsylvania, have invented a new and useful Improvement in Stereoscope-Cases; and I do hereby declare that the following is a full, clear, and exact description of the construction and operation of the same, reference being had to the annexed drawings, forming a part of this specification, in which—

Figure 1, is a perspective view; Fig. 2, a transverse section of the same, like letters indicating the same parts when on the several figures.

The nature of my invention consists in so constructing a stereoscope case, that the part containing the two figures, and that containing the two lenses, may be caused to preserve their parallelism in respect to each other, as they are moved or adjusted to suit the vision of different persons, and at the same time be adapted to close up into a small thin case (like, or resembling the common daguerreotype cases) so as to be conveniently carried about the person, or affixed within a porte monnaie, ladies' work box or dressing case &c. without occupying much space.

Referring to the Figs. 1, and 2, of the drawings—A, is the back part of the case, to which the figures (B, B,) are fixed in any convenient manner.

C, is the front, or lens piece, in which I fix the lenses (D, D,) so as to be directly opposite the two figures, respectively.

E, E, E, are three connecting pieces of equal lengths, jointed in their middle (a, a, a,) and attached also, by joints (b, b, b,) to the lens and figure pieces (at their two ends and bottom edges) so as to fold or double upon themselves respectively within the case when it is closed—or, become straightened, or folded either inward or outward, the parallelism of the front and back, or lens piece and figure piece, being at the same time preserved thereby, during the moving of the same to or from each other, as the visual organs of different persons may require for a proper binocular effect.

It will be perceived that the front and back, or lens and figure pieces of a stereoscope case constructed as described and shown in the drawings, will preserve a perfect parallelism in relation to each other, at

whatever distance they may be separated, 55 and that the most perfect binocular effect is always surely attainable—and that the whole apparatus, when closed, need not exceed the size of a common daguerreotype case. In the mode of construction above described, it is contemplated to make use of the front piece, (C) which contains the lenses, (D, D,) as the outside cover or lid for the figure piece, the lenses being exposed.

From the peculiar combination and arrangement of the lens and figures pieces of stereoscope cases as herein described, they become well adapted for application to porte monnaies, ladies' work boxes, dressing cases, &c., and it is contemplated to fix them there-in, by making use of the lid of such cases for holding the figures, and attaching the lens piece by means of the jointed pieces (E, E, E,) or their equivalents as described, using an outside flap or cover proper, over 75 the lens piece, or not, as expediency may suggest or require.

I am aware that an adjustable single flap, for holding the lenses in daguerreotype cases has been in use, but not being capable of 80 preserving a parallelism, so as to suit the visual organs of different persons, it does not possess or afford the accuracy and perfection required in perfect stereoscopic cases—the attainment of which accuracy and 85 perfection, in a reduced and convenient case, is the object and result of my invention.

The jointed pieces (E) of Figs. 1 and 2 may be made of thin brass pieces hinged together—or, they may be made of paste board 90 or any other suitable material, having their joints made of leather, or parchment, and the whole covered with velvet or other suitable material.

Having thus described the construction 95 and operation of my invention, I proceed to state that I do not claim constructing a stereoscope case with a single adjustable flap, or supplementary lid within the case as such invention has been made and used 100 before in daguerreotype cases—But

What I claim as my invention and desire to secure by Letters Patent, is—

Constructing a stereoscope case with the three jointed pieces (E, E, E,) or their equivalents, so applied as to preserve at all 105 times a perfect parallelism between that part of the case containing the lenses and

the part which contains the figures, so that a perfect stereoscope is formed of the whole as described, and the two figures (B, B,) by binocular vision, are apparently formed into a solid figure—the whole being at the same time adapted to fold or close into a small flat case (resembling the common daguerreo-

type case) that may be conveniently carried about the person, if so required, substantially as described.

JOHN STULL.
